UNITED STATES PATENT OFFICE.

HARRY J. FLOOD, OF CHICAGO, ILLINOIS.

BRICK-PRESS.

1,268,226.

Specification of Letters Patent.

Patented June 4, 1918.

Application filed September 28, 1917. Serial No. 193,634.

To all whom it may concern:

Be it known that I, HARRY J. FLOOD, a citizen of the United States, residing at Chicago, in the county of Cook and State of Illinois, have invented a certain new and useful Improvement in Brick-Presses, of which the following is a specification.

My invention relates to machines for compressing material into form, especially brick presses. The invention is especially applicable to presses of the type wherein there are vertically moving plungers coöperating with each other in molds, the material being fed into the mold by a charger, which also delivers the compressed material onto a table or apron after it has been raised to the level thereof by the rising lower plunger. My invention enables a machine of this type to make wedge brick and arch brick even of material having little or no plasticity or fluidity. Machines of the type mentioned can operate with more or less satisfaction on certain of the more plastic materials without the aid of my invention, but upon other materials of less plastic nature, such machines are practically if not entirely inoperative without my invention unless the function of the invention be performed by hand. To illustrate, a brick press of the type mentioned may by providing top and bottom plunger plates of the proper obliquity be made without the aid of any special attachment or modification to operate on clay having the usual amount of plasticity. The clay "flows" so to speak, from one part of the mold to the other and accommodates itself to the differences in the thickness at different parts of the mold. But there are other materials from which it is desirable to produce bricks, which have little, if any, of the ability to thus "flow" and accommodate themselves in the mold. For example, magnesite is used for the production of fire brick. This substance is granular and gritty, and heretofore the only way that arch or wedge brick could be made from it was by stopping the machine each time after the mold had been filled and removing by hand some of the material from the point where the brick was to be thinner. The charger filled the molds full, that is, flush with the top, and some of the magnesite had to be taken out by hand at the thinner portions of the brick before the plungers could be safely permitted to make the compression. This method was not only slow, but was uncertain in its re-

sults, for the results depended each time upon the skill and judgment of the operator in removing the surplus material. The object of my invention is to provide means for automatically removing the surplus material. In carrying out my invention in the form illustrated, I provide means which dips into the mold on each return stroke of the charger and removes from it, at the proper point and in the proper amount, the surplus material.

I accomplish my object by the mechanism illustrated in the accompanying drawings, in which:

Fig. 1 is a side elevation chiefly in vertical section, showing those parts of the press with which my invention is particularly concerned.

Fig. 2 is a perspective view of a wedge brick, the product produced by the particular mechanism shown in Fig. 1. It will be noted that this brick is of constant width but is thinner at one end than at the other.

Fig. 3 is a front elevation, partly in section, of the parts shown in Fig. 1.

Fig. 4 is a plan view of the mold table, charger, and associated parts including the mechanism embodying my invention in the form shown in Figs. 1 and 3.

Figs. 5 to 7 inclusive show the machine equipped to make arch brick, a sample of which is shown in Fig. 8. Fig. 5 is a side elevation, partly in section, of the mold table and associated parts equipped with mechanism embodying my invention.

Fig. 6 is a front elevation, partly in section, of the parts shown in Fig. 5. This figure shows that for arch brick the greatest amount of material is removed from the side of the mold instead of from the end as in making wedge brick.

Fig. 7 is a sectional view, similar to Fig. 5, showing the lower plunger raised and the charger moving forward to deliver the brick to the front apron. The scraper is shown swung back by the plunger and sliding over it.

Fig. 8 is a perspective of an arch brick produced by the mechanism shown in Figs. 5 to 7. It will be noted that it is of constant width but thicker at one edge than at the other.

Similar numerals refer to similar parts throughout the several views.

I will first describe the mechanism shown in Figs. 1 to 4.

As brick presses of the type mentioned are well known, the press in the present case need not be described in detail. It has a stationary mold table 1 supported by the main frame 2 and having end liners 3 and side liners 4. Fastened to the mold table is a back apron 5 and a front apron 6. The lower plungers 7 are supported on the lower crosshead 8 and furnished at the top with the plunger or die plates 9. The upper plungers 10 are supported on the upper crosshead 11 and provided with plunger or die plates 12. The crossheads move vertically under the action of well known mechanism and cause the plungers to compress the material in the mold. The lower plungers also assist in delivering the compressed material, for they eject it by raising it to the top of the mold, after which the forwardly moving charger 13 delivers it onto the front apron. The charger travels across over the top of the molds under the action of the connecting rods 14 and has an opening 15 at the front through which the material drops down into the molds. The material is supplied from an appropriate chute (not shown) and the supply from the chute is cut off when the charger is forward by a suitable platform or cutoff 16 at the rear of the charger. At the sides of the opening 15 are bars 18 which support a crossbar 19 at the front. Bar 19 forms the front wall of the charger, thus confining the material at the front and, on the backward motion, scraping the surplus material away from the molds so as to leave the molds full to a point level with their tops.

Briefly, the operation of the parts thus far described may be stated as follows: Assuming the lower plungers to be at the bottom of the mold and the upper plungers raised, as shown in Fig. 3, the charger moves forward, its opening 15 containing a supply of material which is pushed forward by the charger and drops into the mold as the charger advances. The molds will be more than filled, and as the charger travels on its return journey, the front wall 19 removes all material lying above the top of the molds, scraping said material backward onto the mold table and back apron and leaving the molds full to a point flush with the top. The plungers then coöperate to compress the material, and after the material has been compressed, the upper plungers rise clear of the molds and the lower plungers rise for the purpose of elevating the compressed material to the level of the mold table so that it may be removed from the machine.

To produce arch brick and wedge brick, the plunger plates must, of course, be beveled; that is to say, their acting surfaces must, in a type of machine like the one shown, be inclined to the horizontal. The inclination may be in a direction transverse

to the machine, as shown in Fig. 6 to produce arch brick shown in Fig. 8, or, longitudinal as shown in Fig. 1 to produce wedge brick, shown in Fig. 2. The principle is practically the same in either case.

I will now describe the novel parts of the machine by which it becomes possible to produce either arch or wedge brick out of magnesite and similar material which is gritty and has a very low coefficient of fluidity. Reference will first be had to Figs. 1 to 4 inclusive. Mounted crosswise in the charger is a shaft 22 which acts as a pivot for side arms 23. While the construction may be varied, I have in the present instance shown the pivot shaft as journaled in bushings 24 mounted in the charger and having collars 25 which act as spacers to keep the side arms at the proper distance from the sides of the charger, as best shown in Fig. 4. These side arms are held in place by keys 26 passing through the slotted ends of the shaft. A cross bar 28 is rigidly fastened at the front of the side arms 23 at a slight distance in front of the front end of the charger. This crossbar is rigidly fastened, being, in the design illustrated, rabbeted into the ends of the arms. Said crossbar is preferably removable, being fastened by nuts 30 screwing onto studs 31 projecting from the ends of the crossbar and passing through the side arms. Fastened to the crossbar is a set of plates 32, one plate for each mold. These plates are the full width of the mold for removing therefrom a portion of the contents as the charger moves on its return journey. As intimated, the function of the plates is to excavate from the mold cavity material in such manner that when the plungers produce the compression, the density of the compressed material will be substantially uniform notwithstanding the fact that the material is substantially non-fluid and the plunger plates approach each other more closely at one part of the mold than at another. The side arms 23, which cause the excavator or scraper plates 32 to go through the proper motions, are operated by cam mechanism, the shape of which is clearly shown in Fig. 1. In the design illustrated, the cams are in two parts 35 and 36. These are plates, the lower edges of which have cam surfaces for acting upon the anti-friction roller 37 mounted upon one of the side arms 23. Of course, these cams and their co-operating roller could be reproduced on the opposite side of the machine, but in the present case they are shown on one side only and it has been found in practice that this usually is sufficient.

The cam plates 35 and 36 are bolted to a plate 38, fastened by brackets 39 to the main frame 2. The design of these parts may, however, be considerably varied without de-

70

parting from the spirit of the invention. As the charger travels back and forth, the roller 37, being acted upon by the cam plates, causes the side arms to oscillate about the pivot shaft 22 and thereby produce a vertical movement in the scraper plates 32. The parts are so designed that in traveling rearward, the plate 32 will drop sharply into the mold at the front end and gradually rise as they travel backward, thus removing or excavating a greater amount of material from the front of the mold where the plunger plates approach each other more closely than at the back where they do not come so closely together. When the plates have finished their backward journey, they leave an inclined surface of material, the surface at the back of the mold being flush with the top of the mold as graphically suggested in Fig. 1. When the plates are traveling forward they will retrace the path traversed in moving backward, but at this time the mold will be empty. The forward end of the side arms 23, and consequently the excavator plates are held down to their work by a spring 40 which, in the form shown, is a helical compression spring, the upper end of which abuts a bracket 41 fastened to the side of the charger and the other end abuts a bracket 42 fastened to one of the side arms.

Referring now to Figs. 5 to 8, inclusive, I have shown a form for making arch brick. In this case the scraper or excavator plates 44 remove more material from one side of the mold than the other instead of operating as the previously described form does in removing more material from the front of the mold than from the back. The mechanism, when adapted for arch brick construction, is the same as before, except that cams of different configuration are employed, and the scraper or excavator plates instead of being rigidly attached to the side arms 23, yield rearward at the bottom. The cams, which for convenience are formed in three pieces, 45, 46 and 47, are bolted to the plate 38, as before. They are so configured, however, as to cause the scrapers in passing backward to dip sharply into the mold at the front and travel horizontally backward until they almost reach the back of the mold, whereupon they rise sharply to clear the back end mold-liner 3. Instead of the fixed cross bar 28, a rotatable cross bar 50 is substituted, as best shown in Fig. 6. This has trunnions 51 at the ends which are journaled in the side arms 23. Consequently, the plates are rotatably suspended. They are permitted to swing rearward but prevented from swinging forward by arms 53 which are rigidly fastened to the squared ends of the trunnions and engage stop pins 54 projecting from the side of the arms 23. The purpose in thus permitting the scraper

plates to swing rearward is illustrated in Fig. 7 where it will be seen that in order to bring the lowest portion of the compressed material flush with the mold table for delivery, it is necessary to bring the highest 70 part of the lower plunger plate 9^a above the level of the mold table. This projecting portion of the plunger plates would interfere with the forward motion of the scraper plate were it not for the rotatable suspension 75 described.

It will be clear that the machine may be readily converted for the making of one style of brick or the other. If ordinary brick are required the only thing necessary 80 is to put in the proper plunger plates and remove the scraper plates. If wedge brick are required the plunger plates are changed and the fixed scraper plates put in. If arch brick are required the plunger plates are 85 again changed, the swinging scraper plates supplied, and the appropriate cam plates affixed.

As a result of my invention, an ordinary brick press may be made to operate automatically on substantially non-fluid materials such as magnesite without danger of straining any of the parts and without producing a brick having greater compression at one portion than at another. Of course, 95 it will be understood that the terms "arch brick" and "wedge brick" are simply trade terms for bricks in which two surfaces are non-parallel and the terms are used in this specification merely to facilitate an understanding of the principle of the invention. 100

Having thus described my invention, what I claim as new and desire to secure by Letters Patent, is:

1. Organized mechanism having a mold, a 105 charger for filling it and means on the charger for removing from within the mold a portion of the material deposited in it by the charger.
2. In mechanism of the class described, a 110 mold, a reciprocating mold charger, and means on the charger descending into the mold for removing part of its contents.
3. A machine for compressing material into form having a mold; plungers for compressing the material in the mold, a charger passing over the mold for filling it, and a scraper dipping into the mold for removing from the mold cavity a portion of the uncompacted material deposited in it by the 115 charger.
4. A brick press having a mold open at the top, plungers for compressing the material in the mold, a reciprocating charger traveling over the top of the mold and means 125 reciprocating with the charger and moving vertically to remove from the mold cavity a portion of the contents thereof.
5. A brick press having a mold, means for compressing the material in the mold, a re- 130

reciprocating charger traveling over the top of the mold, arms pivoted on the charger, a scraper for removing from the mold a portion of the material deposited therein by the charger, said scraper being carried by the arms, and means for oscillating the arms about their pivots for operating the scraper.

6. A brick press having a mold open at the top, plungers for compressing the material in the mold, a charger traveling horizontally back and forth over the mold, a main frame supporting the mold, arms on the charger movable relatively thereto, a plate carried by the charger for excavating a portion of the material from the mold, and cam mechanism partly on the main frame and partly on the arms for operating said bars and plate.

7. A brick press having a mold open at the top, means for compressing the material in the mold, a charger reciprocating horizontally over the mold, a main frame supporting the mold, arms pivoted to the charger, an excavating plate carried by the charger, and cams on the main frame acting upon said arms for operating them and the excavator plate as the charger reciprocates.

8. A brick press having a mold, plungers for compressing the material in the mold, a main frame supporting the mold, a reciprocating charger, side arms pivoted to the charger, an excavator plate carried by the

side arms, cam mechanism partly on the main frame and partly on the side arms for oscillating said bars about their pivots, and springs acting upon the side arms for yieldingly holding them and the excavator plate down to their work.

9. A brick press having an open top mold, means for compressing the material in the mold, a main frame supporting the mold, a charger reciprocating over the mold, side arms pivoted to the charger, an excavator plate carried by the side arms, anti-friction rollers on the side arms, and cams on the main frame coöoperating with said rollers for operating the side arms and excavator plate.

10. A brick press having an open top mold, means for compressing the material in the mold, a charger traveling across the mold, side arms mounted on the charger and movable relatively thereto, means for moving the side arms relatively to the charger, and a scraper carried by the side arms for excavating a portion of the material from the mold, said scraper being yieldable in one direction and non-yieldable in the other whereby it is rendered non-active when traveling in one direction across the mold and active when traveling in the other direction across the mold.

In witness whereof I have hereunto subscribed my name.

HARRY J. FLOOD.
